UNITED STATES PATENT OFFICE.

GEORGE H. NOBLE, OF LOWELL, MASSACHUSETTS.

IMPROVEMENT IN STEPS FOR SPINDLES.

Specification forming part of Letters Patent No. 72,531, dated December 24, 1867.

To all whom it may concern:

Be it known that I, GEORGE H. NOBLE, of Lowell, county of Middlesex, and State of Massachusetts, have invented new and useful Improvements in Spindle-Steps used on Cotton, Woolen, or Flax Machinery.

The nature of my invention consists in providing a case with a capped step, which, when inserted in its seat, forms an oil flask or chamber for the reception of oil to lubricate the bearing of the spindle.

To enable others skilled in the art to make and use my invention, I will proceed to describe its construction and operation.

Figure 1 represents a plan of the case with my improved spindle-step inserted. Fig. 2 represents a section through A and B. Fig. 3 represents a side elevation of my improved spindle-step. Fig. 4 represents a plan of the same.

a represents the case; *b*, the spindle-bearing; *c*, the oil chamber or flask; *e*, the distributing oil-holes; *i*, the receiving oil-holes; *j*, the cap to the step; *l*, the bottom step-fit; *n*, the top step-fit; *m*, the hole for removing the step, and *k* the spindle-step.

Ordinarily, in steps for this purpose, owing to the great speed of the spindle, a constant and sufficient supply of oil is indispensable. If this is neglected, and the step fails to be lubricated, the friction causes heat, and the step is almost instantly worn out. Hence arises the necessity of a receptacle or chamber for oil, with suitable ducts or holes leading from the chamber to the spindle, and when filled with oil, the cap prevents dirt or any particle of matter from fouling or making the oil impure and unserviceable. In my improve-

ment these serious objections are avoided and entirely remedied.

I construct the case *a* with a bearing, *l*, and hole *m*, the hole *m* for the purpose of inserting a proper instrument to remove the spindle-step *k* when required for cleaning or changing for a new one. The step *k* being finished with a bearing, *b*, for the reception of the spindle, the cap *j* is formed to fit the hole in the top of the case *a* by reducing the step *k* in size below the cap *j*, to fit the bearing *l*. The holes *e* and *i*, for the reception and distribution of oil, are then made. The step *k* is then placed in the case *a*, down on and in the socket *l*, which brings the cap *j* below the top of the case sufficient to conduct the oil from the can, through the holes *i i*, into the oil chamber or flask *c*, formed below.

Thus it will be seen the cap *j* is for a double purpose—protects the chamber from dirt, and also firmly holds the top of the step *k*, causing the spindle always to run true, firm, natural, and easy, as this is essential and important, and facilitates the manufacture of good yarn.

I do not claim the distributing oil-holes *e e*, nor the case *a*.

What I claim as my invention, and desire to secure by Letters Patent, is—

The spindle *k*, with its cap *j*, receiving-holes *i i*, and distributing-holes *e e*, and case *a*, the whole constructed, arranged, and combined substantially as and for the purpose herein specified.

GEO. H. NOBLE.
